(57) **CLAIM**

The ornamental design for a cycle belt, as shown and described.

DESCRIPTION

FIG. 1 is a perspective view of the cycle belt of my new design.

FIG. 2 is an top plan view thereof.

FIG. 3 is a front elevational view thereof.

FIG. 4 is a bottom plan view thereof.

FIG. 5 is a rear elevational view thereof.

FIG. 6 is a left side elevational view thereof, with reference to FIG. 1; and,

FIG. 7 is a right side elevational view thereof, with reference to FIG. 1.

The broken line figure shown in FIG. 1, depicting a portion of a human body, is an environmental element and is not a part of my new design.
